(57) **CLAIM**

The ornamental design for a rim and tire protector, as shown and described.

DESCRIPTION

FIG. 1 is a left side view of a rim and tire protector in accordance with my design;

FIG. 2 is a right side view thereof;

FIG. 3 is a top side view thereof;

FIG. 4 is a bottom side view thereof;

FIG. 5 is a back side view thereof;

FIG. 6 is a front side view thereof; and,

FIG. 7 is a side perspective view thereof.

It is understood that the break lines in FIGS. 1, 2, 3, 4, and 7 show a diamond pattern that repeats throughout the circumference of the rim and tire protector as best shown in FIG. 5.
